UNITARY SECTIONABLE CONTAINERS

James Cage, Valley Stream, N.Y., assignor to Reynolds Metals Company, Richmond, Va., a corporation of Delaware

Filed May 17, 1957, Ser. No. 659,997

1 Claim. (Cl. 229—4.5)

This invention relates to containers for materials, where- in each container holds a continuous body of material but has a plurality of sections which are separately removable with different portions of the body of material.

The packaging of materials which are to be consumed a little at a time, has long presented a problem. One answer to the problem is to package the product in a plurality of separate containers, which are assembled in a larger package, by nesting or otherwise. Such packaging is expensive, and it is not always convenient to extract the product from the separate containers; e.g., in the case of shortening and ice cream. In the case of containers for grease, the suggestion has been made in Fisher Patent No. 1,560,681 that the grease be wrapped in a spirally wound tube of paperboard, with circumferential perforations to facilitate tearing away successive sections of the tube in order to expose successive portions of the grease for ready removal. That form of packaging is open to the serious objection, in the case of perishable foodstuffs and the like, that perforations would destroy the hermetic integrity of the tube, and consequently a better means of providing a satisfactory sectionable container for food products and the like has continued to be sought.

In accordance with the present invention, food products and other materials are conveniently packaged in containers which have substantially rigid wall sections, and a flexible sheet of impermeable material to hold the walls together in unitary, sealed relation. When a portion of the contents is to be removed from the container, the connecting layer of impermeable material is cut through around the joint between adjacent wall sections, which releases one or more of the wall sections so that the portion of the contents within the detached section or sections may conveniently be removed therefrom. A strong container is thus provided which has hermetically sealed side walls, and yet is readily severable into separate sections containing measured amounts of the packaged product. The invention further provides end closures to complete the package, and one or both of the end closures is replaceable on the next section after the preceding section has been removed. The recapped container is useful for storing the remaining balance of the contents, and visibly indicates how much of the contents remains.

The embodiments of the invention suitable for particular purposes are varied, and for a better understanding of the invention reference is now made to the present preferred embodiments thereof which are shown, for purposes of illustration only, in the accompanying drawings. In the drawings:

Fig. 1 shows a semi-diagrammatic section taken through the axis of a container embodying the invention;

Fig. 2 shows an enlarged view of a portion of Fig. 1;

Fig. 3 is a perspective view, in reduced scale, of the container shown in Fig. 1;

Fig. 4 is a view corresponding to Fig. 1, but showing the cap and upper section detached from each other, from

2

the balance of the container, and from the whole body of material packaged in the container;

Fig. 5 is a view corresponding to Fig. 3, after the upper section has been removed and the cap has been replaced;

5 Referring now more particularly to the drawings, and initially to the embodiment illustrated in Figs. 1-5, a single body of material 10 (e.g., shortening) is poured into a container 14, which preferably has a loose liner 12 (e.g., foil or paper). The side wall of the container 10 14 is composed of a series of inner cylindrical rings 16 of substantially rigid material (e.g., paperboard), arranged in abutting end-to-end relationship to form a cylindrical inner wall, and a series of like outer cylindrical rings 18 similarly arranged to form a cylindrical outer 15 wall. The inner and outer rings can be of different materials, but are preferably of the same materials, and are relatively slidable against each other. The joints where the inner rings 16 abut each other are offset relative to the corresponding joints between the outer rings 18, and 20 each of the inner rings 16 is adhesively secured to one of the rings 18, so that a series of telescoping nesting sections 20, each consisting of an inner ring 16 and an outer ring 18 (Fig. 4), are created. The assembled sections 20 are secured together by a sheet of flexible impermeable 25 material adhesively secured around the outside of the rings 18. Such sheet could be applied also, or alternatively, around the inside of the rings 16. The said sheet is preferably on the outside and in the form of a label 22 consisting of printed aluminum foil 24 laminated to a 30 paper backing 26 (Fig. 2). The outer circular edges of the rings 18 are preferably beveled to create grooves 28 around the joints where the outer rings 18 abut. The label 22 is preferably pressed at least partly into said grooves 28 in order to indicate where the label should 35 be cut to sever the sections 20 from the container.

Metal or like plates 30 and 31 close the opposite ends of container 14. The top plate 30, which is preferably recessed, is tightly crimped around the upper end of a top ring 18' of the same diameter as the rings 18. When 40 the plate 30 is in closed position, the ring 18' abuts the top edge of the adjacent ring 18 therebelow, and the lower surface of the flat central area of the plate 30 abuts the top edge of the adjacent ring 16. The plate 30 and ring 18' together form a removable and replaceable cap 32 for the container 14. The bottom plate 31 is preferably 45 of the same shape as the plate 30, and is crimped around the lower ends of a like bottom ring 18''. A bottom ring 16'' is secured to the bottom ring 18'' and has its lower edge abutting the inner recessed surface of the plate 31. The ring 16'' is preferably of the same diameter and 50 length as the rings 16, and the ring 18'' is of such lesser length that the upper edges of the rings 16'' and 18'' are positioned to abut the lower edges of the rings 16 and 18 next above. The label 22 extends around the 55 whole outside surfaces of the rings 18' and 18'', and the plates 30 and 31 overlap and crimp around the label 22 to form sealed closures at the ends of the container.

When the material 10 is to be consumed, the label 22 is slit around the grooves 28 between the cap 32 and the next section 20, and between that section and the section immediately below it. The cap 32 and the uppermost section 20 are then detached from each other and from the balance of the container, as shown in Fig. 4, leaving the upper end of the body of the material 10 with its liner 12 exposed. The liner 12 is then pulled 65 away from the material 10, and severed by drawing it against the upper edge of the adjacent ring 16. A length of exposed material 10 is thus presented for convenient removal, as by a blade drawn across the upper edge of the adjacent ring 16. In that manner, a measured amount 70 of the material 10 is obtained for consumption, and the remaining body of material in the container has its upper

surface flush with the upper edge of the said adjacent ring 16, so that the said remaining material will be engaged by the plate 30, without an intervening air space, when the cap 32 is replaced. The liner 12 is not essential, but it is useful in preventing the cap and container sections from brushing against material 10 during opening and closing. When more material is required, the cap 32 is again removed, the next section 20 is lifted away, the liner 12 is again torn away against the upper edge of the next ring 16, the exposed material is again removed, in a measured amount determined by the vertical length of the rings 16, and the cap 32 is replaced to again close the container. The container thus diminishes in contents in measured amounts, and at the same time diminishes in outward appearance, so that the consumer can tell at a glance when the supply of material has been reduced to a point where additional material should be obtained.

The containers of the invention have the advantage of indicating to the consumer how much of the packaged product remains in the package, and of saving the space 20 in crowded refrigerators, freezers and other storage places, which is wasted by partially-filled containers of conventional construction.

While I have illustrated and described present preferred embodiments of the invention, and methods of practicing the same, it will be recognized that the invention may be otherwise variously embodied and practiced within the scope of the following claim.

I claim:

A sectionable container comprising a bottom plate; 30 a bottom wall section including a bottom outer ring extending upwardly from said bottom plate, and a bottom inner ring having the lower portion of its outer surface adhesively secured to the inner surface of said bottom outer ring, said bottom inner ring extending for a substantial distance above the upper edge of said bottom outer ring; a plurality of intermediate wall sections telescopingly superposed above said bottom wall section in the shape of a tube, each said intermediate wall section including an inner ring having the lower part of its outer surface adhesively secured to the upper part of the inner

5 10

surface of an outer ring, each said inner ring having an outer diameter substantially equal to the inner diameter of the outer ring, each said intermediate outer ring having its lower part surrounding the upper part of an inner ring next below in slidable telescoping engagement; a cap closing the upper end of the container, said cap including a top plate and a top outer ring extending downwardly from the edge of said top plate, said outer top ring having an inner diameter substantially equal to the outer diameter of said intermediate inner rings, said top outer ring surrounding the upper part of the inner ring of the intermediate wall section located next below, said outer rings having abutting edges and being beveled around their outer edges to form grooves at the joints where the outer rings abut; and, a substantially impermeable sheet adhesively secured to the outer surfaces of said top, intermediate, and bottom outer rings, said sheet extending integrally across said joint between said outer rings, said sheet being indented into said grooves to provide externally-visible markings at said joints, said sheet initially forming a substantially-impermeable barrier and a connecting element around the container, but being severable around said joints between adjacent sections to permit them to be separated from each other.
